CLAIM

The ornamental design for a wearable personal security device, as shown and described.

DESCRIPTION

FIG. 1 is a top front perspective view of the wearable personal security device in a first aspect of the disclosure. FIG. 2 is a front view of the wearable personal security device of FIG. 1;

FIG. 3 is a rear view of the wearable personal security device of FIG. 1;

FIG. 4 is a right side view of the wearable personal security device of FIG. 1;

FIG. 5 is a left side view of the wearable personal security device of FIG. 1;

FIG. 6 is a top view of the wearable personal security device of FIG. 1; and,

FIG. 7 is a bottom view of the wearable personal security device of FIG. 1.

The broken lines represent structure or features that form no part of the claimed design.
